UNITED STATES PATENT OFFICE.

CLAYTON M. HOFF, OF CLEVELAND, OHIO, ASSIGNOR TO THE GRASSELLI CHEMICAL COMPANY, OF CLEVELAND, OHIO, A CORPORATION OF OHIO.

MANUFACTURE OF ALKALI-METAL PHOSPHATES.

No Drawing.

Application filed July 17, 1924. Serial No. 726,634.

To all whom it may concern:

Be it known that I, CLAYTON M. HOFF, a citizen of the United States, residing at Cleveland, in the county of Cuyahoga and State of Ohio, have invented certain new and useful Improvements in the Manufacture of Alkali-Metal Phosphates, of which the following is a specification.

This invention relates to a process for 10 the manufacture of alkali metal phosphates.

As is known, the alkali metal phosphates are usually prepared by reacting upon alkalies with crude solutions of phosphoric acid such as are produced by dissolving 15 natural phosphates in sulfuric acid. Such crude solutions of phosphoric acid contain relatively large amounts of impurities such as iron, aluminum, calcium, etc., in solution, and if it is attempted to prepare monoalkali 20 metal phosphates by the addition of the requisite quantity of alkali, for instance caustic soda or soda ash, thereto the impurities which are soluble in acid remain in solution and contaminate the product. Consequently 25 the preparation of the monoalkali metal phosphates in this way is not satisfactory. The di-alkali metal phosphates may be prepared in a satisfactory manner by neutralizing crude solutions of phosphoric acid with, for instance, soda ash. In 30 this case the impurities referred to precipitate and may be separated from the solution prior to the recovery for instance by crystallization of the di-alkali metal salt.

The solution, however, retains some colored 35 impurities, either organic or colloidal inorganic or both, which unless they are removed or decolorized discolor the di-alkali metal phosphate product. In the preparation 40 of the tri-alkali metal phosphate a solution of the di-alkali metal phosphate is prepared as described, and after the separation of precipitated impurities is treated with caustic alkali. This process is objectionable on account 45 of the cost of the caustic alkali.

The present invention is designed primarily for the production of the monoalkali metal phosphates and the tri-alkali metal phosphates from the di-alkali metal phosphates which, as stated above, may be economically prepared from crude phosphoric acid and soda ash, although as will appear hereinafter the process may be carried out in such a way as to produce caustic alkali 50 or phosphoric acid or both or any of the

three alkali metal phosphates or intermediate products, that is, mixtures thereof.

The process in accordance with my invention consists generally in subjecting solutions of alkali metal phosphates to direct 60 current electrolysis in a diaphragm cell. The electrolysis dissociates the alkali metal phosphates into alkali metal and phosphate ions of which the alkali metal ions migrate to the cathode compartment of the cell 65 where they discharge and unite with water liberating hydrogen and forming caustic alkali, while the phosphate ions migrate to the anode compartment and discharge and react with water forming phosphoric acid 70 and liberating oxygen. Hydrogen and oxygen liberated at the cathode and anode respectively are thus produced as by-products of the process. The decomposition of water with the liberation of hydrogen and oxygen 75 during the electrolysis results in the concentration of the solution and thus assists the subsequent recovery of the products in pure form from the solution. The caustic alkali and phosphoric acid formed in the 80 cathode and anode compartments, respectively, react with the alkali metal phosphates present therein, forming new alkali metal phosphates.

The electrolysis may be continued until 85 all of the alkali metal is transferred to the cathode compartment and all of the phosphate to the anode compartment, thus producing caustic alkali and phosphoric acid, or the electrolysis may be stopped at any 90 desired intermediate point.

The process is illustrated in the following description of an example of the preferred procedure in accordance with my invention for the preparation of the mono and 95 tri alkali metal phosphates from the di-alkali metal phosphates. In this description reference is made to the sodium phosphates as representative of the alkali metal phosphates.

A solution of di-sodium phosphate prepared in any suitable manner, for instance by the neutralization of crude phosphoric acid with soda ash and separation of precipitated impurities and concentrated or diluted if necessary to the desired concentration, is supplied to a diaphragm electrolytic cell where it is subjected to electrolysis.

The electrolysis may be carried out in a variety of ways.

For instance, the anode and cathode compartments of a diaphragm cell provided with inert electrodes such as lead and a diaphragm capable of resisting the corrosive action of 5 the electrolyte may be filled with a disodium phosphate solution and subjected to electrolysis to an extent just sufficient to form the mono-sodium phosphate in the anode compartment and the tri-sodium phosphate in 10 the cathode compartment, and the resulting solutions discharged and the cell refilled with di-sodium phosphate solution and the operation repeated. This procedure is intermittent. A better procedure is to continuously 15 supply a solution of di-sodium phosphate to the electrolytic apparatus and continuously withdraw the mono and tri phosphate solutions. This may be done by providing a cell of sufficient length between the 20 inlets and outlets that the di-sodium phosphate solution entering at one end may be converted to solutions of the mono and tri sodium phosphates in the anode and cathode compartments, respectively, by the time it 25 reaches the other end. The rate of flow of the electrolyte and the current density can of course be varied with respect to the length of the cell and its volume capacity and the concentration of the electrolyte so as 30 to secure the desired conversion of the solution during its flow from the inlets to the outlets of the cell. The cell in this case should be so constructed, preferably long and narrow and free of abrupt turns and 35 obstructions, as to avoid agitation and mixing of the flowing electrolyte. Still another specific form of apparatus which may be preferred is a plurality of relatively small individual electrolytic cells arranged so that 40 the electrolyte will flow through them in series. This arrangement prevents the mixing of electrolyte which has been converted by electrolysis with fresh electrolyte and permits a careful regulation of the electrolysis 45 so that finished mono and tri sodium phosphates free of any excess of either phosphoric acid or caustic soda may be delivered from the anode and cathode compartments, respectively. Such a series of units of cells 50 is in effect a single cell.

The alkali metal phosphate solution delivered from the electrolytic cell or cells may be treated in any suitable way, for instance for the recovery of the salts in solid form, 55 by crystallization. In some cases it may be desirable to produce only the mono-sodium phosphate or the tri-sodium phosphate and this may be done, assuming that the tri-sodium phosphate is desired, by supplying 60 a di-sodium phosphate solution to the electrolytic apparatus, withdrawing the tri-sodium phosphate solution from the cathode compartment as final product, treating the mono-sodium phosphate solution delivered 65 from the anode compartment with soda ash

sufficient to convert it to the di-sodium phosphate and returning the resulting solution with the di-sodium phosphate supply to the cell. In like manner the tri-sodium phosphate produced by the electrolysis may be 70 converted by the addition of crude phosphoric acid to the di-sodium phosphate and returned to the cell and the mono sodium phosphate only withdrawn as the final product. 75

It will be apparent from the foregoing description that the process is capable of a great variety of modifications for the production of different products. For instance, by the electrolysis of mono-sodium phosphate di-sodium phosphate and phosphoric acid may be made or the electrolysis of any of the alkali metal phosphates may be continued to the production of caustic soda and phosphoric acid. Further variations of the 80 process include the supplying of different solutions to the respective compartments of the electrolytic cell. But from a commercial point of view at the present time the most important application of the process is for 85 the conversion of di-sodium phosphate to mono-sodium phosphate or tri-sodium phosphate or both. 90

The controllable factors in the process are the rate of flow and concentration of the 95 electrolyte and the current density of the electrolyzing current. In a given apparatus the length and capacity of the cell are fixed, although in case a plurality of small unit cells connected in series are used the number 100 of units in operation may be varied.

The principal control of the process therefore depends upon the rate of flow of the electrolyte, the current density and the concentration of the electrolyte. As to the concentration of the electrolyte this factor may be varied practically at will without effect upon the results; that is, the process is operative throughout a very wide range of 105 concentrations. It is therefore preferred to use a relatively concentrated solution in order to minimize its bulk and to facilitate the crystallization of the alkali metal phosphates from the electrolyzed solutions. The temperature of the solution may be elevated 110 in order to permit the use of more concentrated solutions, that is, to increase the solubilities of the salts. The electrolyte may be heated by the passage of electric current, that is by the use of a high current density, or it may be heated by the application of external heat. The current density also may vary within very wide limits. A current density of 7.5 amperes per square foot has been used successfully. 115

In the production of a particular product, for instance, tri-sodium phosphate, variations in the extent of electrolytic action upon the solution may be equalized by discharging the electrolyzed solution into a 120 125

relatively large tank so that if an excess of phosphoric acid is present in one portion of the solution, due to deficient electrolysis, it may be neutralized by electrolyzing the flowing solution at a later stage, so that it will contain a sufficient excess of caustic soda to neutralize the excess phosphoric acid. Or the composition of the solution collected may be adjusted by the necessary addition of phosphoric acid or caustic alkali.

A further feature of the process of my invention is that the solutions of alkali metal phosphates are bleached by the electrolysis as a result of which handsome white crystals are obtainable by crystallization without further purification of the solutions.

My invention therefore provides a simple and economical process for the manufacture of alkali metal phosphates and particularly mono-sodium phosphate and tri-sodium phosphate which is capable of easy and accurate control and in which the several factors are capable of wide variation. The process does not involve any factors such as high temperature, which are difficult to secure or maintain. The process may be carried out in a continuous manner if desired and gives a highly satisfactory commercial product without any special purification.

I claim:

1. Process which comprises subjecting a solution of an alkali metal phosphate to electrolysis in a diaphragm cell and separately recovering the alkali metal phosphate contents of the anode and cathode liquors.

2. Process as defined in claim 1 in which the solution subjected to electrolysis contains dialkali metal phosphate and in which monoalkali metal phosphate and trialkali metal phosphate are recovered from the anode and cathode liquors respectively.

3. Process as defined in claim 1 in which the solution is flowed continuously through the cell and in which the rate of flow and concentration of the solution are adjusted with respect to the current density of the electrolyzing current to produce the desired conversion of the alkali metal phosphate supplied to other alkali metal phosphates.

4. Process which comprises supplying a solution containing di-sodium phosphate and colored impurities to the anode and cathode compartments of a diaphragm electrolytic cell, subjecting said solution to electrolysis whereby mono-sodium phosphate is

formed in the anode compartment and tri-sodium phosphate is formed in the cathode compartment of said cell, and separately withdrawing the bleached solution from said compartments.

5. Process which comprises continuously supplying a solution containing a di-alkali metal phosphate to the anode and cathode compartments of a diaphragm electrolytic cell, continuously withdrawing electrolyzed solution from said compartments, subjecting said solution to electrolysis in its passage through said compartments, and regulating the rate of flow of said solution and the current density of the electrolyzing current to produce monoalkali metal phosphate in the anode compartment and trialkali metal phosphate in the cathode compartment.

6. Process which comprises supplying the anode and cathode compartments of a diaphragm cell with solutions of alkali metal phosphates, subjecting said solutions to electrolysis, and recovering a different alkali metal phosphate from the liquor formed in one of said compartments.

7. Process of bleaching alkali metal phosphates which comprises subjecting a solution thereof to direct current electrolysis in a diaphragm cell, while the solution of alkali metal phosphate is continuously flowing through the cell.

8. Process which comprises supplying a diaphragm electrolytic cell with a solution of an alkali metal phosphate, subjecting said solution to electrolysis, withdrawing solution from one of the compartments of said cell and re-forming therefrom said alkali metal phosphate, and delivering said re-formed alkali metal phosphate into the supply of alkali metal phosphate solution to the cell.

9. Process which comprises subjecting a solution of an alkali metal phosphate to electrolysis in a diaphragm cell, collecting the liquor produced in one of the compartments of said cell in a storage receptacle, and adjusting the alkali metal content thereof to produce the desired alkali metal phosphate.

10. Process as defined in claim 9 in which the solution of the alkali metal phosphate is flowed continuously through the cell and delivered into a storage receptacle.

In testimony whereof, I affix my signature.

CLAYTON M. HOFF.
